UNITED STATES PATENT OFFICE.

CLARENCE C. TRAVIS, OF CHICAGO, ILLINOIS.

DESIGN FOR A COIN-RECEIVER.

41,468.

Specification for Design. Patented June 13, 1911.

Application filed March 27, 1911. Serial No. 617,296. Term of patent 7 years.

To all whom it may concern:

Be it known that I, CLARENCE C. TRAVIS, a citizen of the United States of America, and resident of Chicago, Cook county, Illinois, have invented a new, original, and ornamental Design for Coin-Receipters, of which the following is a specification, reference being had to the accompanying drawing, forming part thereof.

The accompanying drawing is a perspective view of a coin receiver showing my new design.

I claim:

The ornamental design for a coin receiver, as shown.

CLARENCE C. TRAVIS.
